UNITED STATES PATENT OFFICE

2,523,603

CORE RETAINER FOR CENTRIFUGAL MOLDS

Dewey R. Tuggle, Birmingham, Ala.

Application November 13, 1947, Serial No. 785,613

3 Claims. (Cl. 22—166)

1

This invention relates to a tool for use in combination with a cast iron pipe mold. In the manufacture of such pipe it is necessary to insert a baked sand core into the end of the pipe mold in order to have the end of the pipe formed with uniform thickness for making a proper joint. The core used for the purpose has a tapered circumference edge adapted to fit within and adjacent a corresponding tapered face in the end of the mold. It is necessary for the pipe end to be properly finished that the sand core be set in an exact and aligned position, otherwise the piece of pipe will have a defective joining end and cannot be used. At present make-shift devices are used to line up the core resulting in many defective pieces of pipe having to be remade. The present invention provides a simple and highly efficient tool for the purpose.

Further objects are to provide such a tool that will be cheap to manufacture, easy to use, and very durable.

Other objects and advantages will appear from the drawings and description.

By referring to the drawings which are part of this application, it will be observed that Fig. 1 is a part sectional and part full view of the end of a mold showing the sand core therein and the aligning tool attached as used for properly inserting and holding the core in place for casting a piece of pipe; Fig. 2 is a detail view showing one of the cams with notch therein for holding it in place when the tool is in use; Fig. 3 is an end view of the mold with the tool attached; and Fig. 4 is a side view of the end of the mold with the tool in full lines as the tool appears in position for use and the tool in broken lines just before it is seated for use.

Similar reference numerals refer to similar parts throughout the several views.

Referring to the drawings in detail it will be seen that the tool comprises a round shaft 1 with two cams 2 mounted in fixed position thereon. The shaft is provided with a fixed lever handle 3 adapted to turn the shaft and cams. Removably attached by bolts 4 to the mold flange 5 are two brackets 6 with a slot 7 in each adapted for the shaft to fit therein. The sand core consists of a metal angle flange 8 with the sand 9 baked therein. This core is adapted to fit into the end of the mold 10 in tapered position as shown by the taper 11 of the core flange and the taper 12 of the mold. The cams are provided with notches 13.

From the foregoing it will appear that in order to use the tool the two brackets are attached

2

with bolts to the flange end of the mold, then the sand core is set in place for inserting into the end of the mold, then the shaft with fixed cams is placed in the brackets with the lever handle extended outward from the mold end, then the handle is moved to cause the cams to exert pressure evenly against the core flange, to thus press the core into place in an exact and aligned position with its tapered flange face adjacent the tapered face of the mold end. In Fig. 1 the core flange is plainly shown seated at 14 but this seating does not always result because of variations in the sizes of the cores. Such variations are taken care of by the present tool because it inserts the core evenly if not seated to thus insure uniform thickness of the end of the pipe. When the cams are set the notches in the cams prevent them from moving out of fully extended position adjacent the core flange, and in this position 20 the lever handle is parallel with the face of the core as shown in Figs. 1, 3 and 4.

The tool may be made of any kind of metal suitable for the purpose. It also may be made in various sizes to accommodate different sizes of 25 cores in the manufacture or casting of cast iron pipe. Also the tool may be used for other purposes where such a tool is necessary.

While I have shown and described the preferred embodiment of my invention, I do not 30 wish to limit same to the exact and precise details of structure, but reserve the right to make all modifications and changes so long as they remain within the spirit and scope of the following claims.

35 Having described my invention I claim:

1. In a core retainer for centrifugal molds comprising; two supporting brackets, each bracket defining a flat base portion and an extending portion at a 90 degree angle compared 40 to the base portion, a slot in the extended portion of each bracket, the bottom of each slot being half of a circle in shape, a round shaft, said shaft adapted for being supported by its ends in said slots and also being partly revolvable 45 therein, two cams mounted in fixed similar positions on the shaft, a notch in the center of each outer face of each cam, said notches being adapted for retaining the cams in set position on an adjacent flat surface, a lever handle mounted in fixed position on the said shaft with the major axis of the handle at a 90 degree angle compared to the major axes of the said cams.

2. In a core retainer for centrifugal molds of 50 the character described according to claim 1, being further characterized by having bolt and nut

means adapted for attaching its said brackets to a flange placed adjacent the brackets.

3. In a core retainer for centrifugal molds comprising; two identical supporting brackets, each bracket having a flat base portion and an integral extending portion positioned at a 90 degree angle compared to the base portion, each said base portion having a bolt hole therethrough, each said extending portion having a slot formed therein with its bottom defining a half circle shape, each bracket being adapted for being supported for use on a bolt; a round shaft, said shaft adapted for being supported by its ends in said slots and being partly revolvable therein when said brackets are in position for use; two cams mounted and spaced apart on said shaft, a notch in the center of each outer face of each cam, said notches being adapted for retaining the cams in set positions on an adjacent flat sur-

face, a lever handle mounted in fixed position on the shaft between the said cams with the major axis of the handle fixed at a 90 degree angle compared to the major axes of the said cams.

DEWEY R. TUGGLE.
